UNITED STATES PATENT OFFICE.

ELMER G. GARTIN, OF CLAREMONT, NEW HAMPSHIRE, ASSIGNOR TO SULLIVAN MACHINERY COMPANY, A CORPORATION OF MASSACHUSETTS.

FLUID-PRESSURE MOTOR.

Application filed February 26, 1920. Serial No. 361,484.

To all whom it may concern:

Be it known that I, ELMER G. GARTIN, a citizen of the United States, residing at Claremont, in the county of Sullivan and 5 State of New Hampshire, have invented certain new and useful Improvements in Fluid-Pressure Motors, of which the following is a full, clear, and exact specification.

10 My invention relates to fluid pressure motors.

Its object is to provide an improved fluid pressure motor adapted for rock drilling purposes. A further object of my invention 15 is to provide an improved pneumatic motor for rock drilling purposes in which improved and simplified means for short stroking or for varying the force of the blow is embodied. A further object of my 20 invention is to provide improved means cooperating with the valve throwing passages of a fluid pressure motor of the fluid pressure actuated valve type whereby a variation of the length of stroke may be accomplished.

In the accompanying drawings I have shown for purposes of illustration, one form 25 which my invention may assume in practice.

30 In these drawings,

Fig. 1 is a sectional view through the cylinder and rotation mechanism of a drill motor embodying one form of my improved construction.

35 Fig. 2 is a section on the line 2—2 of Fig. 1.

Fig. 3 is a developed section through the cylinder and valve chest thereof showing the valve throwing passages taken on 40 the line 3—3 of Fig. 2.

Figs. 4 and 5 are fragmentary views showing other positions of the valve which controls the throwing of the distributing valve.

45 It is a well known fact that in rock drilling operations, it is frequently highly desirable to be able to rotate the drill steel when backing out of a deep hole in order to prevent sticking of the steel in the hole. At such times it is disadvantageous to continue to strike the steel with a hammer piston as a great strain is then imposed on the tool retainer. It is, however, desirable to continue the supply of fluid pressure to the bore of the steel to blow out the steel. In

motors in which the piston conducts 55 through the rifle grooves thereof a certain quantity of fluid to the hollow steel during the operation of the motor, it is obvious that if the motor could be kept in operation and with the piston reciprocating with a 60 shorter stroke toward the front end of the cylinder, this supply of fluid would not be discontinued although hammering on the steel would be discontinued. It is also at 65 times desirable to reduce the force of impact of the piston upon the steel, while yet continuing to strike a lighter blow. There are already devices for the first of these purposes in commercial use, but I have illustrated in the accompanying drawings and 70 shall now describe a simplified means for accomplishing both of these results.

Referring especially to Fig. 3, it will be noted that I have illustrated a motor having a cylinder 1 of uniform bore in which a piston 2 reciprocates under the action of pressure fluid distributed through ports 3 and 4 which are controlled by a spool valve 5 reciprocating in a valve chest 6. The motor as so far described is of well known 75 commercial form and I do not claim this structure as per se constituting my invention. The piston is provided at its forward end with a rifle bar 7 in which there are arranged spiral grooves 8 through which, 80 when the piston is making its rearward stroke, fluid is transmitted to the hollow drill steel, herein designated as 9. In the motor shown, the valve 5 is normally thrown by cylinder pressure transmitted to the opposite ends of the valve through ports 10 and 11, these ports normally being located 85 in such position as to transmit the throwing fluid from the cylinder to the end of the valve in sufficient time to effect throwing of the valve and reversal of fluid supply in the necessary manner. As illustrated 90 herein, I have arranged the port 11 nearer the rear end of the cylinder than the port 10 is to the front end thereof, this location 95 being due to the fact that the normal throwing port to effect the reversal of the operation of the valve at the end of the forward stroke of the piston is longer than that communicating with the port 10 and accordingly a greater time interval must 100 elapse after the uncovering of the port 11 before the valve will be thrown. In order 105

2
to be able to cause the throw of the valve at varying intervals prior to the instant when the piston reaches the front end of the cylinder and impacts against the steel, 5 I have arranged a valve 15 having a passage 16 extending therethrough, and a peripheral groove 17. The function of this valve is, when in the position shown in Figs. 2 and 3, to connect the port 11 through the return bend 18 in the throwing port through the port 16 in the valve and then to the front end of the valve chest by way of passage 19. But when the valve 15 is turned in a counter-clockwise direction to the extent shown in Fig. 4, the return bend 18 is removed from all communication with the port 11 and with the end of the valve chest and fluid passes direct by way of groove 17 from port 11 to the remaining portion 19 of the throwing passage. Under these circumstances, it will be evident that as the throwing fluid has a less distance to travel, the valve will be thrown at a considerably earlier time in the stroke and accordingly the direction of travel of the piston may be reversed prior to the impact of the striking bar 7 of the piston on the steel.

As my ratchet and pawl mechanism, hereinafter designated 20 and of well-known commercial construction, provides a mechanism for the step by step rotation of the piston in which there is normally one pawl seated, a pawl part way down the tooth and a pawl 35 near the tip of a tooth of the ratchet, it will be obvious that if the stroke be shortened, the rotation mechanism will nevertheless be operative to rotate the steel. This may occur at a reduced rate if the shortening 40 of the stroke is sufficient, but with a design such as is illustrated, the shortened stroke would not be sufficient to effect a slowing down of the speed of rotation. The length of the return bend 18 45 will be approximated by calculation and the precise length to accomplish the desired result will then be determined by actual trial in a drill.

If the valve be turned still further in the counter clockwise direction, it will reach the position shown in Fig. 5 and the passages 11 and 19 will be brought in communication with a small pocket 21, whose volume is sufficiently great to cause, due to the expansion of part of the throwing fluid therein, a less delay than that resulting from the use of the U-bend in the throwing of the valve and a reduced force of impact of the piston on the steel. The function of the pocket 50 is to increase the volumetric capacity of the passage leading to the valve, between the ends thereof, whereby the throwing fluid will not so rapidly build up the pressure requisite to the throw of the valve.

65 From the foregoing description, it will

be seen that I have provided a motor in which a very ready and simple means is provided to prevent impact of the piston on the drill during retraction of the steel, or to reduce the force of the impact, the effect 70 of the pocket being less than that of the return bend, while yet maintaining the usual supply of pressure fluid from the cylinder to the steel and continuing to rotate the same. It will be obvious that the same 75 principle of operation and construction may be adapted to use in other drilling engines such as piston drills or channelers, it being obvious that an increase in length of the throwing passages will delay the instant when the throwing fluid begins to move the valve, and that the insertion of a pocket in the throwing passages will also result in delaying the transmission of a sufficient pressure 80 to the ends of the valve to effect throwing thereof, and that by varying the length of the passage or the capacity of the pocket 85 different results can be secured.

While I have in this application specifically described one form which my invention may assume in practice, it will be understood that this form of the same is shown for purposes of illustration and that the invention may be modified and embodied in other forms without departing from its spirit 95 or the scope of the appended claims.

What I claim as new and desire to secure by Letters Patent is:—

1. A fluid pressure motor comprising a cylinder, a piston therein, a fluid pressure actuated valve controlling the movements of said piston, a throwing passage therefor having a fixed inlet, and means for varying the length of said throwing passage.

2. A fluid pressure motor comprising a cylinder, a piston therein, a fluid pressure actuated valve controlling the movements of said piston, a throwing passage therefor having a fixed inlet, and means for varying the volumetric capacity of said throwing 105 passage.

3. A fluid pressure motor comprising a cylinder, a piston therein, a fluid pressure actuated valve controlling the movements of said piston, a throwing passage therefor having a fixed inlet, and means for varying the length of said throwing passage and its volumetric capacity.

4. A fluid pressure motor comprising a cylinder, a piston therein, a fluid pressure actuated valve controlling the movements of said piston, a throwing passage therefor, and means for alternately varying the length of said throwing passage or its volumetric capacity while maintaining its length constant.

5. A fluid pressure motor comprising a cylinder, a piston therein, a pressure actuated valve controlling the movements of said piston, a throwing passage for said

valve having a single inlet, and a valve controlling said throwing passage to increase the length thereof.

6. A fluid pressure motor comprising a cylinder, a piston therein, a pressure actuated valve controlling the movements of said piston in said cylinder, a throwing passage for said valve having a single inlet, and a valve controlling said throwing passage to increase the volumetric capacity thereof between its ends.

7. A fluid pressure motor comprising a cylinder, a piston therein, a fluid pressure actuated valve controlling the movements of said piston, a throwing passage for said valve, a control valve located between the ends of said passage, and means whereby said valve may cut off a portion of said passage between the ends thereof and directly connect the remaining portions.

8. A fluid pressure percussive motor comprising a cylinder, a piston therein, a fluid pressure actuated valve controlling the movements of said piston, a throwing passage for said valve, a return bend in said passage, and a valve adapted to connect said return bend between the ends of said passage and to bridge the passage while shutting off said return bend.

9. A fluid pressure percussive motor comprising a cylinder, a piston therein, a fluid actuated valve controlling the movements of said piston, a throwing passage for said valve, a pocket adapted to be connected to said throwing passage between its ends, and a valve controlling said connection.

10. A fluid pressure percussive motor comprising a cylinder, a piston reciprocable therein, a throwing passage for said valve, a return bend communicable with and adapted to increase the length of said passage, a pocket communicable with said passage and adapted to increase the volumetric capacity thereof, and means controlling the connection of said return bend and of said pocket with said passage.

11. A fluid pressure percussive motor comprising a cylinder, a piston reciprocable therein, a throwing passage for said valve, a return bend communicable with and adapted to increase the length of said passage, a pocket communicable with said passage and adapted to increase the volumetric capacity thereof, and means controlling the connection of said return bend and of said pocket with said passage com-

prising a valve adapted to connect said return bend with said passage, to interconnect the remaining portions of said passage directly, and to connect said pocket with said passage upon successive movements.

12. A fluid pressure percussive motor comprising a cylinder, a piston reciprocable therein, a throwing passage for said valve, a return bend communicable with and adapted to increase the length of said passage, a pocket communicable with said passage and adapted to increase the volumetric capacity thereof, and means controlling the connection of said return bend and of said pocket with said passage comprising a valve adapted to connect said return bend with said passage, to inter-connect the remaining portions of said passage directly, and to connect said pocket with said passage at different times.

13. A fluid pressure motor comprising a cylinder, a piston therein, and means for controlling the movements of said piston in said cylinder including a pressure controlled valve, a throwing passage therefor communicating therewith and with the bore of said cylinder and controlled by said piston, and means for increasing the capacity of said passage between its points of communication with the cylinder and valve.

14. A fluid pressure motor comprising a cylinder, a piston therein, and means for controlling the movements of said piston in said cylinder including a pressure controlled valve, a throwing passage therefor communicating therewith and with the bore of said cylinder and controlled by said piston, and means for increasing the length of said passage between its points of communication with the cylinder and valve.

15. A fluid pressure motor comprising a cylinder, a piston therein, and means for controlling the movements of said piston in said cylinder including a pressure controlled valve, a throwing passage therefor communicating therewith and with the bore of said cylinder and controlled by said piston, and means for increasing the capacity of said passage between its points of communication with the cylinder and valve while maintaining its length constant.

In testimony whereof I affix my signature.

ELMER G. GARTIN.
